RAILWAY BRAKE RIGGING

Stephen J. Angle, Schenectady, N. Y., assignor to
 American Locomotive Company, New York,
 N. Y., a corporation of New York

Application March 14, 1951, Serial No. 215,577

3 Claims. (Cl. 188—56)

1

This invention relates to railway brake rigging. In a well known design of railway truck, the outboard pull rods of the brake rigging are disposed in close proximity to underslung frame-supporting equalizers. Whenever it has been necessary to remove the frame of such a truck from the wheel and axle assemblies, as in the case of repairs, it has been the practice to entirely disconnect the brake rigging from the frame. This has been necessary since the connections between the outboard pull rods and the levers adjacent the equalizers have been inaccessible for disassembly.

The object of the invention, therefore, is to provide for use on a railway truck a clasp brake rigging that can be readily disassembled whenever it is desired to remove the truck frame from the wheel and axle assemblies. A further object is to provide such rigging, including a pull rod parallel to and in proximity with the equalizers, so constructed that the end of the pull rod adjacent the equalizer may be readily disconnected from the remainder of the rigging, thereby to permit the easy removal of the truck frame from the wheel and axle assembly. A further object is to provide such brake rigging, including a pull rod in close proximity to the equalizer, so constructed that the end of the pull rod adjacent the equalizer may be readily disconnected from the remainder of the rigging when the rigging is in operative position on the truck. Still another object is to provide a novel connection between a lever and the pull rods of a brake rigging that can be readily disconnected when the brake rigging is in operative position on a truck. Other and further objects of the invention will appear from the following description, the accompanying drawing and the appended claims.

In the drawing, Fig. 1 shows a fragmentary side elevation of a railway truck construction having a brake rigging to which the arrangement of the invention is applied; Fig. 2 is an end view taken along the line II—II of Fig. 1, some of the elements of Fig. 1 being eliminated to simplify the view; Fig. 3 is an enlarged view taken in elevation of the connection between a lever and a pull rod which forms part of the invention; Fig. 4 is an enlarged section view taken along the line IV—IV of Fig. 1; and Figs. 5 and 6 are perspective views of detail parts.

Referring to the drawing, journal box 10 is mounted conventionally upon the journal 11 of wheel 12 of one of the wheel and axle assemblies of a railway truck. To facilitate description, the wheel and axle assembly shown will be considered

2

to be the rear assembly. A pair of underslung equalizers 13 rest at their rear ends upon the journal box 10 and extend longitudinally of the truck frame 14, the opposite or front ends (not shown) of the equalizers resting upon the journal box of the front wheel and axle assembly (not shown). Although a pair of equalizers are here illustrated, it is of course understood that the invention will be applicable if only one equalizer should be found preferable. A pair of hanger levers 15, pivotally supported at 16 by the truck frame, are provided intermediate their ends with a brake head 17 pivoted therebetween at 17a. Head 17 carries a shoe 18 adapted for frictional braking engagement with the rim of wheel 12. The lower ends of levers 15 are connected by pin and slot means 19 to pull rods or straps 21 and 22, the connection being adjustable by means of a slack adjuster 20.

A second pair of hangers 23 are separately pivoted at 23a to opposite sides of the truck frame and carry between them at their lower ends a brake head 24, equipped with a brake shoe 25 for frictional engagement with the rim of wheel 12. Brake lever 26, which is a live lever, is actuated by conventional power cylinder means (not shown), and is pivotally secured at 26a intermediate its ends to hangers 23 and brake head 24. Lever 26 is arranged between hangers 23, as best seen in Fig. 2, and at its lower end is pivotally connected at 27 to pull rods 21 and 22 by a device best shown in Fig. 4 and later more fully described. It should be here noted that the pivotal connection 27 (see Fig. 2) is relatively inaccessible for disassembly because of the proximity of the inboard equalizer 13 and the nearness of the rail R. In the prior art, it has been the practice, in the event it should be desired to lift the truck frame from the wheel and axle assembly, to entirely disconnect the brake rigging assembly from the frame on one end and from the actuating mechanism at the other. In the illustrative embodiment, this would mean disconnecting hangers 15 from the frame at pivots 16 and lever 26 from its actuating mechanism at pivot 28. It would also mean disconnecting hangers 23 from the frame at pivots 23a. To avoid such a time-consuming and inconvenient practice, the device of the invention has been designed.

In the original assembly of the truck, hangers 15 and 23 are pivoted to the frame, and lever 26 is operatively connected to hangers 23. This sub-assembly is lowered into position upon the equalizers and the pull rods 21 and 22 are then connected to hanger 15 at 19. Pull rods 21 and

22 are next connected to lever 26, as will now be described. The lower end of lever 26 has an enlarged portion or hub 31 formed with smooth parallel faces 32 and 33. A bore 34 extends through hub 31, its axis being normal to the planes of the parallel faces. Hub 31 is considerably shorter on the side toward the equalizer than on the opposite side so that there will be clearance between the face 32 and the equalizer in order to permit the connection to be made between the pull rod and the lever. Bushing 36, prior to the sub-assembly, has been press-fitted into bore 34 of lever 26 so that its end portions 37 and 38 extend somewhat beyond the faces 33 and 32 respectively; and before the sub-assembly is lowered into position, bolt 39 is inserted through the bushing with its hexagonal head 41 disposed loosely on the short side of hub 31. Head 41 has a larger diameter across the corners than the inside diameter of bushing 36 so that passage of bolt therethrough in an inboard direction is prevented. After the sub-assembly is lowered upon the equalizers, pull rod 21 (which has already been connected to lever 15) is positioned upon end portion 38 by passing hole 35 over head 41 and pull rod 22 (already connected to lever 15) is positioned upon end portion 37 by passing its hole 35 on to such end portion. Washer 42 and lock-washer 43, are loosely applied to the inboard end of bolt 39 and nut 44 is run down on threads 45 sufficient for temporary assembly. Allowance is made in such temporary assembly for longitudinal movement of the bolt to the left again so that its head 41 may be moved toward the equalizer to permit retainer member 46 to be applied to the bolt to act as a washer between bolt head 41 and pull rod 21. Retainer 46 is thereupon positioned flush against the outboard side of pull rod 21 and curved seat 47 of notch 46' is brought into engagement with the shank of the bolt. The radius of seat 47 is equal to or slightly greater than the radius of the bolt shank.

Pull rod 21 is formed with a conventional adjusting hole 49 which is used for taking up slack in the rigging when the brake shoes are worn down. Hole 49 is now used for the further purpose of locating retainer 46. Retainer 46 has a hole 50 which will be aligned with the hole 49 when retainer 46 has been positioned flush against the pull rod. Plug 51 is inserted into hole 49 from the inboard side of the outboard pull rod 21 and is provided with an annular flange 52 to abut the inboard side of the pull rod. Central aperture 53 of the plug will be aligned with hole 50 of retainer member. Bolt 54 is then inserted from the inboard side through holes 53 and 50 and a small nut 55 is applied thereto. Of course any suitable means to lock retainer 46 in place by utilizing hole 49 will suffice, the plug and bolt and nut arrangement merely being illustrative of a preferred means. Nut 44 is now run down tightly so that bolt head 41 tightly secures retainer 46, pull rod 21, washers 42 and 43, and pull rod 22 against the lateral faces of the enlarged hub of the lever. Bolt 54 serves to prevent retainer 46 from backing out of position in case the assembly should loosen under the wear and tear of operating conditions. Since bolt 54 is not subjected to heavy forces, it is of relatively small dimensions. It will be apparent from the foregoing discussion that retainer 46 is reversible. If lever 26 is connected to adjusting hole 49 after wear of the brake shoes has occurred, then retainer 46 is reversed to permit plug 51 to be

inserted in hole 35 of pull rods 21 and bolt 54 and nut 55 are assembled through the plug to hold retainer 46 in place. Then the assembly shown in Fig. 4 is the same except that hole 49 is used instead of hole 35 in pull rod 21. The function of the parts is identical to that previously described.

With the construction heretofore described, disassembly of the levers 15 and 26 from pull rods 21 and 22 is easily accomplished. Nut 55 is easily removed with a small wrench and bolt 54 is pulled out from the inboard side. Nut 44, which is easily accessible for an operator's wrench, is backed off so that bolt 39 and bolt head 41 may be moved to the left, as seen in Fig. 4. Retainer 46 is then easily knocked out of engagement with the bolt shank. Pull rod 21 may then be pulled laterally off bushing 36 and over bolt head 41 and dropped down. Pull rod 22 is disconnected from engagement with bushing 36 after nut 44 has been run off and washers 42 and 43 removed from bolt 39.

While there have been hereinbefore described approved embodiments of this invention, it will be understood that many and various changes and modifications in form, arrangement of parts and details of construction thereof may be made without departing from the spirit of the invention, and that all such changes and modifications as fall within the scope of the appended claims are contemplated as a part of this invention.

What I claim is:

1. In a railway truck of the class wherein underslung equalizers are disposed adjacent the brake rigging on the outboard side thereof and in close proximity thereto, in combination, hanger means suspended from the truck frame on opposite sides of a wheel to carry clasp brake shoes; a live lever connected to the first of the hanger means; a pair of pull rods arranged on the inboard and outboard sides of said wheel and connected at one end to the live lever and at the other end to the other of the hanger means, the connection between said pull rods and the lever being in close proximity to an equalizer and comprising a bolt having an integral head disposed on the outboard side of the connection and a shank extending through the pull rods and the lever pivotally connecting the same, the outboard pull rod having a hole therethrough adapted to pass over the bolt head; a retainer member between the bolt head and the outboard pull rod; means to lock the retainer member in position and means on the inboard side of the lever to draw the bolt head and the retainer member against the outboard pull rod thereby to maintain the pull rods in pivotal connection with the lever, said retainer member being removable when the inboard drawing means is loosened thereby to permit the outboard pull rod to be passed over the bolt head for disengagement of the connection between said pull rod and the lever.
2. A combination, according to claim 1, in which the retainer member has a notch to engage the bolt shank.
3. In a railway brake rigging, a connection between a live lever and a pair of pull rods comprising a hub on the lever having a bore therethrough, a bushing extending through the bore to form supporting means for the pull rods, a bolt having an integral head disposed on the outboard side of the connection and a shank extending through the pull rods and the bore pivotally connecting the rods and lever, the outboard lever

having a hole therethrough adapted to pass over the bolt head, a retainer member between the bolt head and the outboard pull rod, means to lock the retainer member in position and means on the inboard side of the lever to draw the bolt head and the retainer member against the outboard pull rod thereby to maintain the pull rods in pivotal connection with the lever, the arrangement of the elements being such that upon loosening of the drawing means the retainer member may be removed from the connection and the outboard pull rod may be moved over the bolt head.
